ROTARY INDEX

Filed Aug. 12, 1929

Inventor:
George L. Hinman,
by Faber & Elmer,
Attn'y's.

UNITED STATES PATENT OFFICE

GEORGE L. HINMAN, OF NEW HAVEN, CONNECTICUT, ASSIGNOR TO THE GREIST MANUFACTURING COMPANY, A CORPORATION OF CONNECTICUT

ROTARY INDEX

Application filed August 12, 1929. Serial No. 385,156.

This invention relates to an improvement on the rotary directory or index covered by U. S. Patent No. 1,496,515 and the invention has for its object to obviate a trouble sometimes arising in the use of the device of the patent just referred to. The directory or index of the said patent comprises two reels and an index strip or web which may be rolled up on either of the said reels and which is caused to travel very rapidly from one reel to the other by spinning or rapidly twirling a knob on an operating shaft which is geared to the shafts on which the reels are mounted. In thus rapidly rolling the index web or strip from one reel to another a sudden jerk is liable to occur on the ends of the index web or strip when fully unwound from one of the reels, these sudden jerks sometimes breaking or tearing the said web or strip, which, as the device has been commercially constructed, is of paper. It has been attempted to obviate this difficulty by yieldingly connecting the ends of the index web or strip to the reels through the medium of springs, but this yielding connection has not entirely obviated the trouble referred to, but which has been satisfactorily obviated by the present invention which provides a yielding stop, as will be hereinafter fully set forth.

In the accompanying drawing Fig. 1 is a vertical section similar to Fig. 3 of the drawings of the patent above referred to. Fig. 2 is a vertical section with the gearing illustrated in Fig. 1 omitted, to show the present invention in detail. Fig. 3 is a detail view of a portion of an index strip adapted for cooperation with the parts shown in Fig. 2. Fig. 4 is a detail plan view of the yielding stopping device and a portion of the shaft on which it is mounted.

Referring to the drawing, 11 denotes a portion of a casing within which is mounted an operating shaft 19, which, in practice, is provided with a knurled knob to enable it to be rapidly twirled. Secured to the shaft 19 is a gear wheel 22 meshing with a smaller gear wheel 23 rotating on a stationary shaft 24, said gear wheel 23 being fixed with relation to a large gear wheel 25 rotating on said shaft 50 and meshing with pinions 26 secured to shafts

28 carrying the reels 27 with which the opposite ends of the index web or strip 31 are connected.

This connection of the index strip with the reels 27 has been effected by providing said index strip at each end with an eyelet 12, these eyelets being engaged by hooks 13 at the ends of springs 14 attached to the reels, thus making a yielding connection of the said strip with the said reels. In turning the shaft 19 by its knob the accelerating gearing above referred to will impart a very rapid movement to the reels, and as some of the parts of the rotating mechanism of the device are purposely made somewhat heavy there will be considerable inertia to be overcome when the rapid travel of the index strip is to be arrested.

When the index strip 31 is fully wound up on one of the reels and is entirely unwound from the other reel, as shown in Fig. 2, it is desirable that the rotation of the reels should be yieldingly arrested to avoid such a sudden jerk on the index strip as would be likely to tear the same. To this end the present invention comprises a one-piece stopping device loosely mounted on the shaft 24 and comprising two spring arms 15, connected by a loop 15^b encircling said shaft 24, the said spring arms being arranged to overlie the convolutions of the index strip when said strip is fully or partly wound on the said reels. In the construction shown in Fig. 2 one arm of the said spring stopping device is shown as resting on the fully wound-up strip on the upper reel, while the other arm of said spring lies against the outer surface of the lower reel in such a position that when the lower end of the strip is wholly unwound from the lower reel a projection or hook 13 on a spring 14 attached to said reel will abut against the lower spring arm of the said stopping device, turning it slightly on the shaft 24, thus causing the other spring arm of the said loosely mounted stopping device to press against the wound-up strip on the upper reel. This pressing of a spring arm on the wound-up strip serves as a brake to assist in arresting the rotation of the reels which are geared together. The hooks 13 on the springs 14 serve as projections or

abutments carried by the reels and which co-operate with the yielding stop afforded by said spring arms 15 and their connecting loop 15^b.

5 To prevent displacement of the yielding stopping device longitudinally of the shaft 24 the latter is preferably provided with lugs 15^a on opposite sides of the loop 15^b. These lugs may be struck up from said shaft and will 10 permit only a slight movement of the stopping device longitudinally of said shaft, as will be obvious.

From this it will be understood that the 15 said two-arm stopping device affords a yielding stop which will arrest the rotation of the reels when a projection or hook 13 abuts against an end of either of the arms 15 of the said yielding stopping device; and this yielding stopping device, in arresting the travel of 20 the index strip, will act in such a manner that there will be no danger of tearing said strip, as will be understood.

In the successful operation of the rotary index, to which the invention relates, a certain 25 amount of slack of the index strip between the reels is necessary to permit said strip to run freely between the reels in rapidly running said strip from one reel to the other. When the end of the strip is reached at one reel the 30 momentum sometimes causes the end part of the strip to be doubled and jammed by backlash, and this trouble, heretofore occurring, is prevented by the stopping device of this invention.

35 The invention is not to be understood as being limited to the specific construction of the yielding stopping device, herein described, or the use of the same in connection with hooks on springs attached to the reels to afford stopping projections, as variations of these features might be made within the limits of mechanical skill, without departing from the 40 scope of this invention as defined by the claims hereunto appended.

45 Having thus described my invention, I claim and desire to secure by Letters Patent:—

1. In a rotary index, the combination with 50 an index strip and reels on which said strip may be rolled, and from one to the other of which it may be caused to travel rapidly, of a one-piece yielding stopping member comprising two spring arms partly overlying said reels, said arms being connected by a 55 loop, a shaft on which said loop is loosely mounted, and yielding abutments carried by said reels, said abutments being arranged to come in contact with the ends of said spring arms; whereby, when the said index strip is 60 fully unwound from a reel, a yielding abutment on the empty reel will strike against the end of a spring arm of said stopping member and will turn said loop slightly on said shaft thus causing the other arm of said 65 stopping member to exert a braking pressure

on the wound-up index strip on the other reel.

2. In a rotary index, the combination with 70 an index strip and reels on which said strip may be rolled, and from one to the other of which it may be caused to travel rapidly, of a one-piece yielding stopping member comprising two spring arms partly overlying said reels, said arms being connected by a 75 loop, a shaft on which said loop is loosely mounted, and yielding abutments carried by said reels, said abutments consisting of springs attached to said reels and having, at 80 their free ends, hooks arranged to come in contact with the ends of said spring arms; whereby, when the said index strip is fully unwound from a reel, a yielding abutment on the empty reel will strike against the end of a spring arm of said stopping member and will turn said loop slightly on said shaft thus 85 causing the other arm of said stopping member to exert a braking pressure on the wound-up index strip on the other reel.

3. In a rotary index, the combination with 90 an index strip and reels on which the said strip may be rolled and from one to the other of which it may be caused to travel rapidly, of a yielding stopping device for arresting the travel of the said index strip when one end thereof is fully unwound from one of said 95 reels, said stopping device consisting of a loosely mounted member having two spring arms partly overlying said reels and co-operating with projections carried by said reels, and one of which projections abuts 100 against the end of one of said spring arms when said index strip is fully unwound from a reel, a shaft on which said member is mounted, said shaft having lugs to retain said member in place.

In testimony whereof I affix my signature.
GEORGE L. HINMAN.
